UNITED STATES PATENT OFFICE.

BENJAMIN S. REYNOLDS, OF MILWAUKEE, WISCONSIN, ASSIGNOR TO CHAIN BELT COMPANY, OF MILWAUKEE, WISCONSIN, A CORPORATION OF WISCONSIN.

WATER-SCREENING APPARATUS.

1,191,115.

Specification of Letters Patent. Patented July 11, 1916.

Application filed May 12, 1916. Serial No. 97,043.

To all whom it may concern:

Be it known that I, BENJAMIN S. REYNOLDS, a citizen of the United States, residing at Milwaukee, in the county of Milwaukee and State of Wisconsin, have invented certain new and useful Improvements in Water-Screening Apparatus, of which the following is a specification.

My invention has for its object to improve water screening apparatus so as to make it practically possible to use a comparatively short screen in situations where the water level varies greatly from time to time.

15 In the accompanying drawings I have illustrated a typical installation of flume screen embodying my improvements.

Referring to these,—Figure 1 is a vertical sectional view of the apparatus. Fig. 2 20 is a face view of the same. Fig. 3 is a horizontal sectional view on the line III—III of Fig. 1.

In the drawings, 2 indicates a stream from which water is taken, to be delivered, 25 through intake pipes or tubes 3, to an industrial plant. These pipes connect with a chamber 4 in which the screened water collects before it is led off through the pipes. The chamber 4 lies behind a dam or partition 30 5 that separates it from the stream 2, and through this dam are formed a plurality of openings 6, one above the other, and each of a size sufficiently large to permit the flow of a volume of water such as 35 35 may be required by the plant when working at its maximum capacity. Fitting in each opening 6, or covering them, are coarse stationary screens or gratings 7 adapted to intercept the coarser bodies that may be carried by the water, such as cakes of ice, pieces 40 40 of wood, etc.

8 indicates an adjustable gate adapted to close the openings 6. It is represented as being supported by vertical guides 9 secured 45 to the face of the wall or partition 5. It is of a size to cover one of the openings 6, and, in the embodiment of the invention illustrated, is arranged to be adjusted by hand, for which purpose a rod 10 is secured 50 to the gate, this being screw-threaded throughout a portion of its length and engaged by a nut suitably supported, and arranged to be turned by the hand wheel 11. It will be evident from an examination of 55 the drawings that when the gate is adjusted

to one position it uncovers one opening 6 and closes the other.

On the side of the partition 5 opposite the gate 8 is arranged an endless automatically cleaned flume screen 12. This screen 60 is preferably located within the collecting chamber 4. It consists of a supporting frame 13 in which are mounted lower and upper wheels, designated 14 and 15 respectively, upon which are supported an endless 65 screen formed of articulated sections 16. As stated, this form of screen is well known in the art and need not, it is thought, be described more in detail.

The screen is power operated, being represented as driven from a motor 16' through suitable gearing including belting 17 connected with the shaft carrying the upper set of screen supporting wheels 15. The screen 12 is large enough to cover one of 75 the openings 6 so as to intercept any coarse material carried by the water, and is held close to the face of the wall or partition 5 by guides 18.

The screen as a whole is vertically adjustable, so that it may be arranged in operative position opposite either of the openings 6. To permit and facilitate this the guides 18 are vertically disposed and arranged to permit the screen to be moved up and down along them, and the screen is counterweighted as indicated at 19. A hoisting cable 20 is also connected with the screen frame, passing, in its course, over sheaves 21 mounted in a tower or framework 22 supported above the dam or partition 5. The hoisting cable is wound upon a drum 25 arranged to be driven in any suitable manner, as from the motor 16'.

23, 24 indicate gutters for receiving the refuse removed or discharged from the screen surface. The means for cleaning the screen of refuse are not shown or described, as they are well known in the art and may be of any suitable kind.

In Fig. 1 the parts of the apparatus are represented in position for operating when the water is at a low stage or level, as represented at a. Under these conditions the gate 8 is elevated to close the upper opening 6 and the screen is lowered so as to be in operative position opposite the lower, uncovered opening. This latter opening is in such vertical position that it will permit a flow of water through it ample in quantity 105 110

to supply all the needs of the plant, even at the lowest water stage that may be expected to occur in the stream 2. When the parts are thus arranged the water passes freely through the lower opening 6 and is cleansed by the screen 12, the refuse taken therefrom being delivered to and carried away through the lower gutter 23. The water level in the chamber 4 is supposed to be the same as that in the stream 2, since the opening 6 should be more than ample to supply the intake pipe or pipes 3, when the latter are discharging their full capacity. Should the water in the stream rise the parts may remain in the positions just referred to until the level indicated by the dotted line *c* is reached. When this occurs the refuse gutter 23 becomes flooded and the material discharged from the screen cannot be carried off properly but would rather accumulate in the chamber 4 and hence be liable to go to the apparatus of the plant through the intake pipes 3. Whenever the water in the stream is above the level indicated by the dotted line *c*, the parts are adjusted to occupy the positions indicated in Fig. 1 by dotted lines; that is to say, the gate 8 is lowered to uncover the upper opening 6 and close the lower opening, and the screen elevated so as to be in inoperative position opposite the uncovered opening, that is, the upper one. The water from the stream 2 is therefore cut off from the lower opening and is delivered through the upper opening, and under the adjustment just referred to, the apparatus will operate successfully until it reaches the maximum level indicated at *b*. When the water is delivered from the stream through the upper opening the refuse is taken off through the upper gutter 24 which is located at or above the maximum water level.

Should the apparatus be used for screening water taken from a stream in which the water level fluctuates more widely than that indicated in the drawings, a greater number of openings 6, and of refuse gutters or discharge means, should be provided. It is however thought to be unnecessary, for a full understanding of the invention, that an arrangement having more than two openings 6 be shown.

I have illustrated the gate as being supported upon the opposite side of the partition 5 from the screen 12, but, while this is the preferred arrangement, it is not essential to the operation of the apparatus nor to my invention, as all that is required is that the gate should be adjustable so as to cut off the water from one or the other of the openings 6, as may be required.

It is evident from the foregoing description, taken in connection with the accompanying drawings, that a flume screen of comparatively small size, as to length, may

be successfully used in situations where the level of the stream from which the water is taken fluctuates to a much greater extent than the length of the screen. There is thus a saving in initial cost of installation due to the smaller apparatus that is required, and also a saving in running expenses, since the power required to drive the lighter and smaller apparatus is not so great as that required in arrangements such as have heretofore been employed. 75

It will be understood that the belting 17 is shortened whenever the screen is adjusted to the higher position. I therefore prefer to use for this belting sprocket or other form of chain belt, the links of which may be easily separated to permit either the removal therefrom or the addition thereto of sections, as may be required. 80

What I claim is:—

1. In a water screening apparatus, a wall having through it a plurality of openings at different levels, means for closing any of the openings at will, and a vertically adjustable water screen adapted to be moved into position opposite the uncovered opening. 85 90

2. In a water screening apparatus, a wall having through it a plurality of openings at different levels, means for closing the said openings, means for adjusting the closing means so as to close any opening at will, a water screen of a size to treat the water passing through any opening, and means for adjusting the screen into position opposite any unclosed opening. 95 100

3. In a water screening apparatus, a wall having through it a plurality of openings at different levels, means for closing any of the openings at will, an adjustable, self-cleaning, water screen adapted to be moved into position to treat the water flowing through any unclosed opening, and means for receiving and carrying off refuse discharged from the screen arranged at different levels. 105

4. In a water screening apparatus, a wall having through it a plurality of openings at different levels, means for closing any opening at will, a self-cleaning water screen of a size to treat the water supplied by any single unclosed opening, means for adjusting the said screen into working position opposite any opening, and independent means for receiving and carrying off refuse discharged from the screen arranged at different levels so as to receive such refuse as the screen is adjusted to one position or another. 110 115 120

5. In a water screening apparatus, a wall having through it a plurality of openings at different levels, an adjustable gate for closing any one of the openings, means for adjusting the gate, a vertically adjustable water screen of a length to treat the water passing through any single opening, means for adjusting the screen into position oppo- 125 130

site an unclosed opening, separate receivers for the refuse taken up and discharged by the screen, arranged at different levels, and means for operating the screen.

5 6. In a water screening apparatus, a wall separating the source of water supply from the screen having through it a plurality of openings at different levels, a vertically adjustable gate of a size to close any one of the 10 openings, means for guiding and holding the gate so it may be brought into closing position opposite any opening, means for vertically adjusting the gate, a vertically adjustable endless self-cleaning water screen

of a size to treat the water delivered through 15 any single opening, guides for directing the movements of the screen so it may be brought into position opposite any opening, means for vertically adjusting the screen, means for operating the screen, and means 20 for receiving and carrying off the refuse, corresponding in number to the openings in the said wall and located at different levels so as to receive the refuse material discharged from the screen as it occupies a 25 position opposite one or another of the openings.

BENJAMIN S. REYNOLDS.

Correction in Letters Patent No. 1,191,115.

It is hereby certified that in Letters Patent No. 1,191,115, granted July 11, 1916, upon the application of Benjamin S. Reynolds, of Milwaukee, Wisconsin, for an improvement in "Water-Screening Apparatus," an error appears in the printed specification requiring correction as follows: Page 2, line 30, for the word "inoperative" read *operative*; and that the said Letters Patent should be read with this correction therein that the same may conform to the record of the case in the Patent Office.

Signed and sealed this 25th day of July, A. D., 1916.

site an unclosed opening, separate receivers for the refuse taken up and discharged by the screen, arranged at different levels, and means for operating the screen.

5 6. In a water screening apparatus, a wall separating the source of water supply from the screen having through it a plurality of openings at different levels, a vertically adjustable gate of a size to close any one of the 10 openings, means for guiding and holding the gate so it may be brought into closing position opposite any opening, means for vertically adjusting the gate, a vertically adjustable endless self-cleaning water screen

of a size to treat the water delivered through 15 any single opening, guides for directing the movements of the screen so it may be brought into position opposite any opening, means for vertically adjusting the screen, means for operating the screen, and means 20 for receiving and carrying off the refuse, corresponding in number to the openings in the said wall and located at different levels so as to receive the refuse material discharged from the screen as it occupies a 25 position opposite one or another of the openings.
